(57) **CLAIM**

The ornamental design for a shoulder guard for a wire clothes hanger, substantially as shown and described.

DESCRIPTION

FIG. 1 is a top, front and left side perspective view of a shoulder guard for wire clothes hanger showing my design; FIG. 2 is a bottom, back and left side perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown represent unclaimed subject matter and form no part of the claimed design.

1 Claim, 6 Drawing Sheets

FIG. 1

FIG. 2

FIG. 3

FIG. 4

FIG. 6
